UNITED STATES PATENT OFFICE

FORRESTER L. HAMMER, OF BRANFORD, CONNECTICUT

OIL BURNER

Application filed May 23, 1927. Serial No. 193,624.

This invention relates to oil burners, and while the burner shown, which is illustrated and described as a preferred embodiment of my invention, is particularly adapted for use in connection with furnaces for heating houses and other buildings, it will be understood that the principles of my invention are not restricted to this use, but may be used in the combustion of liquid or even powdered fuels for other purposes as well.

A complete oil burner which may be installed as a unit in connection with a furnace must provide for an atomizer to atomize the liquid fuel, a source of compressed air to carry out the atomizing process, means to deliver the air and the fuel oil to the burner nozzle, and usually a supply of air in addition to the atomizing air to support the combustion of the fuel. It is also desirable that the fuel oil be properly filtered in its passage from the tank, or other source of supply to the burner, and that its flow to the burner be controlled by automatically actuated valves so that the flow may be stopped, if for any reason the burner is shut off or the flame is extinguished. Moreover, if it is to be a complete unit, it must be supplied with blower means to furnish the air required for atomization and combustion, and a source of power, usually an electric motor, to operate the blowers. In addition it should be provided with means for igniting the oil when the operation of the burner is begun, and with protecting devices for automatically cutting off the ignition when the burner is lighted, for cutting in the ignition if for any reason the flame is extinguished, and for stopping the operation of all the mechanism of the burner if for any reason the flame is extinguished and the fuel does not re-ignite.

One object of my invention is to provide a unitary oil burner system, the parts of which will be assembled in a compact manner so that the entire unit occupies as little space as possible.

A further object of my invention is to so coordinate all the parts of an oil burner that a compact and efficient structure results, and so that the burner may require a minimum

amount of power in operation, be practically noiseless, and have relatively few parts subject to wear.

Another object of my invention is to provide a unitary oil burner which may be installed in connection with a furnace with very little labor and trouble, and at the same time will be efficient and economical in operation.

A still further object of my invention is to provide an oil burner system with the necessary safe guards so that it may be used with practically no attention on the part of the operator, but, on the other hand, will be substantially automatic in its operation, and at the same time reliable, dependable and economical.

To these and other ends the invention consists in the novel features and combinations of parts to be hereinafter described and claimed.

In the accompanying drawings:

Fig. 1 is a top plan view of an oil burner embodying my invention;

Fig. 2 is a rear elevational view of the same;

Fig. 3 is a side elevational view of the same;

Fig. 4 is a sectional view taken substantially on line 4—4 of Fig. 1;

Fig. 5 is a view taken on line 5—5 of Fig. 4;

Fig. 6 is a sectional view on line 6—6 of Fig. 1, showing the solenoid fuel controlling valve;

Fig. 7 is a section on line 7—7 of Fig. 1, showing the diaphragm operated fuel controlling valve; and

Fig. 8 is a sectional view on line 8—8 of Fig. 7.

The oil burner which I have selected to illustrate and describe comprises a base 10 which may be a casting of suitable shape, supported upon legs 11, 12, 13 and 14, these legs being adjustable in length so that the burner may be supported in proper position from a floor or other supporting base. Upon the base 10 is mounted an electric motor 15, which as shown at 16, may be bolted to the base.

To one side of the base 10 is bolted the housing 17 of the pressure fan, which in this instance is arranged to deliver air under six or eight ounces of pressure to the atomizer 5 for the purpose of atomizing the fuel. At the other side of the base is bolted the housing 18 of the volume fan, which will be described more specifically hereinafter. This housing comprises a relatively large plate 10 secured to the base and a drum 19 within which the fan is mounted, the interior of this drum, as shown in Fig. 4, communicating with the burner housing 20 within which the burner nozzle is mounted. Suitable supporting flanges 21 extend between the housing 18 and the housing 19.

The motor shaft is adapted to extend from both ends of the motor so that it may carry the volume fan and the pressure fan on its 20 respective ends. In this manner the two fans are operated directly from a single motor without the usual intermediate gearing, so that the bearings of the motor shaft are the only wearing parts in the structure. 25 For this purpose one end 23 of the motor shaft extends into the housing 17 of the pressure fan, and the pressure fan 24 is mounted thereon. The other end 25 of the motor shaft extends into the housing 19 of the volume fan, and has mounted thereon the fan 30 rotor 26, as shown in Fig. 4.

The drum 19 of the volume fan has an opening 27 on the side toward the motor to provide an air intake for this fan, this opening being controlled by the shutter 28 pivoted to the housing at 29 and operated by the pointer arm 30 to regulate the effective size of the opening 27, so that the required amount of air will be admitted to the fan 40 housing. This fan consists of a spider 31 having fan blades mounted between annular rings 32, one of which is shown, to blow the required amount of air into the nozzle housing 20 at low pressure.

45 The pressure fan comprises a pair of disks 33 and 34 between which are mounted spiral blades 35, the blades being adapted to take in air at the fan axis through the conduit 36, shown in dotted lines in Fig. 5, and expel 50 this air at six or eight ounces pressure from the collecting ring 37. The intake 36 communicates through the conduit 36^a with one end of an air tube 38, the other end of which enters the housing of the volume fan, and is 55 provided with a cup shaped receiver 39 to receive a part of the air delivered by the volume fan and carry it to the pressure fan. This air, when delivered to the pressure fan, is, therefore, already under a slight amount 60 of pressure, which is stepped up to the required degree by the pressure fan, and passes from the mouth of the collecting ring to the pressure fan delivery tube 40, from which it is carried into the volume fan housing and 65 delivered to the atomizing nozzle through

this housing by the tubes 41 and 42, the atomizing nozzle being shown at 43. It will be understood that atomization is effected by this pressure air delivered from the tube 42. The nozzle 43 is described and claimed specifically in my application, Serial No. 185, 70 616, filed April 21, 1927, and it is not deemed necessary to make a further description thereof in this application.

Surrounding the atomizing nozzle is an 75 air deflector 45, also described more particularly in my prior application referred to. This deflector is provided with a number of spirally shaped blades between which the air passes from the volume fan, and by which it 80 is given a whirling or rotating motion serving to spread the atomizing fuel and to thoroughly mix the volume air therewith. A sleeve 46 surrounds the deflector, and between this sleeve and the walls of the housing 20 are spaces 48 and 49 through which an additional quantity of volume air may 85 pass to the flame. In some instances it has been found that better results are obtained by closing off the opening 48, and in such 90 case the air through the opening 49 tends to deflect the flame downwardly and thus overcome its natural tendency to rise. The flame is thereby kept in a more nearly stationary or "floating" position, so that all of 95 the fuel will be efficiently consumed substantially at the level of the mouth of the housing 20. Two ignition terminals or spark points 50 pass through the deflector 45 between the vanes thereof, one of which is shown in Fig. 4, the other being directly 100 behind the one shown. These spark points are connected by the conductors 51 to the posts 52 and 53 mounted on the housing of the volume fan. From these posts conductors lead to a transformer 54 which steps up 105 the voltage to a sufficient extent to obtain a good spark across the terminals 50 to ignite the fuel.

The oil enters the burner from the source 110 of supply through the pipe 55, and is passed through a filter 56 from which it emerges through the pipe 57. A regulating valve 58 is placed in this pipe to regulate the amount of oil delivered to the burner. Between the 115 pipe 57 and the pipe 59, shown more particularly in Fig. 4, through which the oil is delivered to the atomizing nozzle 43, are placed two valves to automatically control the oil fed to the burner, so that this feed 120 will not begin until the pressure fan delivers air under the required pressure to efficiently atomize the fuel, and so that the oil will be shut off when the burner stops. These valves 61 and 62 are shown more especially 125 in Figs. 6, 7 and 8 of the drawings.

The valve 61 is arranged to be operated by the pressure of the atomizing air, and the fuel enters the housing 63 of this valve from the pipe 57 through a conduit 64, from which 130

it passes into the valve chamber 65 in a downward direction to a chamber 66, from which it is carried by the pipe 67 to the electrically operated valve 62. Within the 5 valve chamber 65 is a spring-pressed valve 68 cooperating with a valve seat 69, and being urged against its seat by the spring 70 which surrounds the valve stem. Below this 10 bumper 71 carrying at its lower end a valve 72 cooperating with the valve opening 73. This bumper is fluted or grooved so as to let the oil pass freely through the chamber 65, the ridges thereof being in substantial contact 15 with the walls of the chamber so that it will be properly guided in its up and down movements. At an intermediate point the bumper is reduced, as shown at 74, to provide shoulders above and below the reduced portion 20 to receive a forked or bifurcated crank arm 75 attached to a rock-shaft 76. Mounted upon this rock-shaft is a bell-crank lever which carries upon one end 77 a weight 78 which normally acts to turn the rock-shaft 25 76 in a counter-clockwise direction so as to maintain the valve 72 in a closed position, and likewise permit the spring 70 to hold the valve 68 downwardly against its seat. In this manner a double seal is provided to 30 effectually close the oil channel and prevent any oil reaching the burner until the atomizing air has reached the required pressure. The other end 80 of the bell-crank lever is provided with a roller or anti-friction device 81, which rests against a diaphragm 82 communicating with the collecting ring 37 through the pipe 82^a and therefore exposed to the pressure created by the pressure fan. When the pressure air has reached the 35 pressure required to effectively atomize the fuel, the arm 80 is moved to the left, as shown in Fig. 7, thus rocking the shaft 76 in a clockwise direction against the action of the weight 78 to raise the valve bumper 71 and 40 open the valves 68 and 72 so as to allow a flow of oil into the chamber 66 and pipe 67.

It will be understood that when the current is turned off the pressure created by the pressure fan 24 would not immediately fall 45 to zero, and hence, even after the current has been cut off from the fan motor, the valves 68 and 73 might remain open or partially open for a certain length of time and permit a continuance of the supply of oil to the 50 nozzle. Some of this oil might continue to flow after the pressure had fallen below the point where efficient atomization is effected, and it hence would not be properly burned. It is, therefore, desirable to provide means 55 to cut off the oil supply immediately that the current to the motor is interrupted, so that any oil which remains in the pipes between the cut-off and the burner will be 60 atomized by the pressure air delivered after 65 the current stops, so that all of the oil which

remains in the delivery tubes will be efficiently burned.

For this purpose, I have provided the valve 62, which is electrically operated by a solenoid 83, as shown in Fig. 6. This solenoid will preferably be in circuit with the motor so that the solenoid valve will be opened when current is supplied to the motor and will be closed when the current is cut off. The oil enters the housing 84 of this valve 70 through the duct 85 from the oil pipe 67, and passes downwardly through the valve chamber 86. Between the conduit 85 and the valve chamber 86 is arranged a pair of valve chambers 87 and 88 having respectively the 75 valve seats 89 and 90 closed by the ball valves 91 and 92 which rest upon these seats. Within the chamber 86 is an armature 93 carrying a valve 94 at its lower end cooperating with a valve seat 95 through the port of 80 which the oil enters the pipe 96 to be delivered to the pipe 59. The armature 93 is provided at its upper end with a bumper 97 designed, when the armature is raised by the 85 energized solenoid, to contact with the ball valve 92 and move it upwardly from its seat, this valve in turn contacting with the ball valve 91 and likewise pushing it from its seat to permit the flow of oil into the chamber 86. It will be understood that the upward movement of the armature likewise carries upwardly the valve 94 so as to permit oil to 90 flow into the tube 96.

It will be understood that this electrically 95 operated valve will be opened as soon as the current is turned on. The oil will not, however, immediately begin to flow through this valve, as it will not be permitted to pass through the valve 61 until the pressure behind the diaphragm 82 has been sufficient to 100 open this valve against the action of the weight 78, so that no oil will be permitted to pass to the burner until air under sufficient pressure is delivered thereto to atomize the fuel. The electrically operated valve 105 is, of course, closed immediately the current is shut off from the motor so that the supply of oil will be stopped at once, notwithstanding the fact that the valve 61 only remains open for a short period of time. The result 110 will be, therefore, that any oil flowing to the burner from the pipe 59 after the solenoid valve is closed will be consumed by the continued supply of air to the burner nozzle, and this arrangement insures that the supply 115 of oil is cut off before the cutting off of the air supply, and as there will be an abundance of air to consume all of the oil permitted to flow to the burner, no unburned oil will remain therein. The pipe 59 is inclined 120 slightly away from the nozzle as shown in Fig. 4, so that the oil will tend to remain 125 in the pipe when the supply is shut off.

A pipe 97^a leads through the housing 20 to a point adjacent the burner nozzle from 130

a point 98 in the base, so that if any oil should leak from the valves 61 or 62 and the associated pipes, it will drop upon the base and be carried to the burner nozzle by this pipe.

5 Adjacent the end of the housing 20, I have arranged a protectostat 99, the details of which it is not necessary to illustrate for the purpose of this application. This protectostat is operated from the radiant heat 10 of the flame of the burning fuel, and will operate to cut off the ignition after the fuel is once ignited. Likewise it will turn on the ignition if for any reason the flame goes out.

15 It is important in oil burners of this character to provide ready access to the parts of the burner which may need to be removed for adjustment, cleaning, or other purpose.

20 To this end I have provided a removable cover 100 for an opening 101 at the top of the housing 20. Likewise a removable cover plate 102 is provided for an opening in the delivery end of the housing 19 of the volume 25 fan. By removing these covers the union 103 may be disconnected and likewise the bolt 104 may be removed to disconnect the air tube 42 from the tube 41. The entire burner nozzle may then be removed from 30 the housing through the opening 101. This may be very readily accomplished with only a few minutes work, and the nozzle may then be conveniently cleaned or adjusted.

It will be understood that my burner may 35 be installed in connection with a furnace by inserting the nozzle of the housing 20 into the ash door of the furnace below the grate line, the front of the furnace being represented by the part 105 which rests against 40 the flange 106 on the housing. The burner would ordinarily extend into the ash pit as far as the shoulder 106.

While I have shown and described a preferred embodiment of my invention, it will 45 be understood that it is not to be limited to all the details shown but is capable of modification and variation within the spirit of the invention and within the scope of the appended claim.

50 What I claim is:—

In an oil burner, a base, a burner nozzle connected to the base, a housing within which the nozzle is mounted, an oil line leading to said nozzle comprising a controlling 55 valve mounted on the base, and a pipe leading downwardly from the base to a point within the housing adjacent the nozzle and providing means whereby leakage oil may flow by gravity from the base to the nozzle 60 to be burned.

In witness whereof, I have hereunto set my hand this 17th day of May, 1927.

FORRESTER L. HAMMER.
